BAG

William F. Stark, Nashotah, and John H. Wahl, Hales Corners, Wis., assignors to Howard B. Stark Company, Pewaukee, Wis., a corporation of Wisconsin

Filed Jan. 16, 1961, Ser. No. 63,562

Term of patent 3½ years

(Cl. D58—2)

FIG. 1 is a front elevational view of a bag showing our new design, the rear of said bag being substantially plain; and

FIG. 2 is a longitudinal sectional view through the bag, taken along line 2—2 of FIG. 1.

We claim:

The ornamental design for a bag, substantially as shown and described.
